(57) **CLAIM**

The ornamental design for a foldable toddler tower, as shown and described.

DESCRIPTION

FIG. 1 is a front, left and top perspective view of a foldable toddler tower showing my new design;

FIG. 2 is a rear, left and bottom perspective view thereof;

FIG. 3 is a front elevation view thereof;

FIG. 4 is a rear elevation view thereof;

FIG. 5 is a left elevation view thereof, a right elevation view thereof being a mirror image of the left elevation view;

FIG. 6 is a top plan view thereof; and,

FIG. 7 is a bottom plan view thereof.

The broken lines depict portions of the foldable toddler tower that form no part of the claimed design.

1 Claim, 7 Drawing Sheets(56)
